(57) **CLAIM**

The ornamental design for a razor cartridge, as shown and described.

DESCRIPTION

FIG. 1 is a perspective view of a design for a razor cartridge of the present invention;

FIG. 2 is a front view thereof;

FIG. 3 is a back view thereof;

FIG. 4 is a top view thereof;

FIG. 5 is a bottom view thereof;

FIG. 6 is a left side view thereof;

FIG. 7 is a right side view thereof; and,

FIG. 8 is another perspective view thereof.

(Continued)

The guard area of the razor cartridge is lined for the color red and the housing area is lined for the color black.
The broken lines illustrate portions of the razor cartridge and form no part of the claimed design.

1 Claim, 6 Drawing Sheets
